DESIGN FOR A CROCHETING STAND OR THE LIKE

Thomas B. Owens, Cleveland, Ohio

Application July 12, 1945, Serial No. 120,676

Term of patent 14 years

(Cl. D3—19)

To all whom it may concern:

Be it known that I, Thomas B. Owens, a citizen of the United States, residing in Cleveland, in the county of Cuyahoga and State of Ohio, have invented a new, original, and ornamental Design for a Crocheting Stand or the like, of which the following is a specification, reference being had to the accompanying drawing, forming part thereof.

I claim:

The ornamental design for a crocheting stand or the like, substantially as shown.

THOMAS B. OWENS.
